CLAIM

The ornamental design for a stacked GBIC guide rail assembly, as shown and described.

DESCRIPTION

FIG. 1 is a perspective view of a stacked GBIC guide rail assembly showing my new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof mounted to a circuit board which is shown in broken lines for illustrative purposes only and forms no part of the claimed design.
